UNITED STATES PATENT OFFICE.

WILLIAM M. BAILEY, OF DETROIT, MICHIGAN, ASSIGNOR TO EDWARD P. GAYLORD, OF SAME PLACE.

INVALID AND SURGICAL CHAIR.

SPECIFICATION forming part of Letters Patent No. 246,652, dated September 6, 1881.

Application filed November 29, 1880. (No model.)

To all whom it may concern:

Be it known that I, WILLIAM M. BAILEY, of Detroit, in the county of Wayne and State of Michigan, have invented an Improvement 5 in Surgical Chairs, of which the following is a specification.

The nature of this invention relates to certain new and useful improvements in that class of chairs which are made adjustable for surgical or other purposes; and the invention consists in the peculiar construction and combination of the various parts, as more fully herein-after described.

Figure 1 is a perspective view of my improved chair in a partially-inclined position and with the leg-rests extended laterally. Fig. 2 is a side elevation, with the upholstery removed, showing the chair in a sitting position, and in dotted lines in an extended reclining position. Fig. 3 is a bottom plan of the chair-back, seat, and leg-rests extended, and with the frame removed.

In the accompanying drawings, which form a part of this specification, A represents the 25 sides of the frame or legs of the chair, secured together by the ties or girts a and braces b, all preferably made of iron. The lower ends of the legs are provided with casters c, and on top with upholstered arm-rests d. A segment, 30 e, of iron, and provided with a segmental slot, h, is securely riveted to the rear leg and to the top, as shown.

B represents the frame for the back. This frame is pivoted at i to the frame A, and its lower 35 end is pivoted at k to the rear end of the seat-frame C, and just in rear of the point k a rod, l, passes through the back-frame and the segmental slots in the segments e. One end of this rod is provided with a head or nut, m, and 40 the opposite end with a lever-cam, n, by means of which the back and its attachments are locked in any desired position. The front end of the seat is pivoted to the side sway-bars o, near their lower ends, and the upper ends of these bars are in turn pivoted to the frame A at p.

The leg-rest D is preferably made of two parts, r and r'. These are hinged to the front ends of the bars s, the rear ends of which are

pivoted to the bar t, which is secured laterally 50 to the seat-frame, and near its rear end. To the rear or under side of the leg-rest are secured the lugs u, to which are pivoted the rods v, the free ends of which terminate in hooks w, which engage with the rod x, which connects the lower ends of the cam-bars y together. The upper ends of these bars are pivoted at a' to the frame A. These bars are provided with cams b', which are designed to engage with the friction rollers or wheels c', 60 which are journaled upon suitable short shafts or bearings projecting from each side of the seat-frame. The seat at its front is cut-away, as shown at d' in Fig. 3, and this cut-away portion is fitted with a removable block, e', 65 which may be upholstered to conform to the upholstery of the seat E. The leg-rests are constructed as described to facilitate surgical operations, and the removable block e' will allow, if occasion require, the patient under treatment to perform the operations of nature into a suitable vessel placed under the opening disclosed by the removal of the block e'.

In practice, the chair being in a sitting position, as shown in Fig. 2, the cam-lever is loosened and the chair-back depressed into a horizontal position. This movement raises the back to the horizontal plane of the pivotal point i, projects the seat forward, and elevates it. In its forward movement the wheels c' upon 75 the side of the seat come into contact with the rear side of the cam b', which forces the lower ends of the bars y forward, and this movement forces the leg-rest up to the plane of the seat; or a less depression of the back will give 80 a reclining position at any desired angle, and the lever-cam will lock the chair in any required position.

What I claim as my invention is—

1. The combination, with the frame A, provided with the slotted segments e, of the back B, pivoted to the frame A, seat-frame C, pivoted at its rear end to the lower end of the back, rod l, passing through the back-frame and slots h, and lever-cam n, whereby the back 90 and seat may be locked in any desired position, substantially as described.
2. The combination, with the frame A, of the

back B, pivoted thereto, seat-frame C, pivoted to the back, and provided with the rollers c', leg-rests r r', pivoted to the seat-frame, and cam-bars y, pivoted to the leg-rests and to the frame A, whereby the depression of the back will elevate the seat and leg-rests to the same horizontal plane with the back, substantially as described.

3. The combination, with the seat-frame C, having the rollers c', of the leg-rests r r', hav-

ing lugs u u, bars s, each pivoted at its outer end to a leg-rest and at its inner end to the lateral bar t, rods v, and cam-bars y, substantially as described, and for the purpose set forth.

W. M. BAILEY.
